(57) **CLAIM**

The ornamental design for a boat rack, as shown and described.

DESCRIPTION

FIG. 1 is a first embodiment of a boat rack showing my new design, the broken-line disclosure of a boat being understood to form no part of the claimed design;

FIG. 2 is an enlarged front elevational view thereof, with the rear being a mirror image of that shown;

FIG. 3 is a right side elevational view of a second embodiment thereof, with the left side being a mirror image of that shown, and the horizontal members being shown broken-away to indicate unclaimed length, the only difference from the first embodiment residing in the element having an unclaimed length;

FIG. 4 is a top plan view of the second embodiment thereof; and,

FIG. 5 is a bottom plan view of the second embodiment thereof.
